A. W. SMITH

TYPEWRITING MACHINE

Filed March 5, 1923

UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

Application filed March 5, 1923. Serial No. 622,715.

My invention relates to typewriting machines and more particularly to work registering mechanism of such machines.

The invention is intended to accomplish some of the same results as the construction disclosed in the patent to Clio B. Yaw, No. 1,012,785, dated Dec. 26, 1911.

One of the objects of the present invention is to provide a construction of the character 10 described which may be readily applied as an attachment to the "improved" or more modern form of the No. 10 and also to the No. 12 Remington typewriting machines without modifying the structural features of said 15 machines as they now exist.

To the above and other ends which will hereinafter appear, my invention consists in the features of construction, arrangements of parts and combinations of devices set forth 20 in the following description and particularly pointed out in the appended claims.

In the accompanying drawings wherein like reference characters indicate corresponding parts in the different views,

25 Figure 1 is a front elevation with parts in section of the counting mechanism together with some of the associated parts of the Remington typewriter common to the more modern style of No. 10 and also to the No. 12 Remington machines; the section being taken on the line 1—1 of Figure 2 and looking in the direction of the arrow at said line.

Figure 2 is a top plan view of the same.

I have only shown so much of the typewriting machine as is necessary to arrive at 35 an understanding of my invention in its embodiment therein. It will be understood, however, that the parts of the typewriter shown with which the features of my invention are associated are common to the more modern style of No. 10 and also to the 40 No. 12 Remington machines.

The power-driven carriage (not shown) carries a feed rack 1, and is mounted to travel 45 transversely over a top plate 2 of the machine under control of the usual escapement mechanism. In said machines the escapement mechanism includes an escapement wheel 3 and a loose dog 4 and a holding dog 5, said 50 dogs coacting with the wheel in the usual manner by an actuation of any printing key or the space key to afford an intermittent letter space feed of the carriage. In said ma-

chines the escapement wheel is fixed on a shaft 6 supported in bearings in a detachably supported bracket 7 that includes yoke-shaped supporting arms 7^a. The forward end 8 of the shaft 6 is supported in a bearing opening in the forward supporting arm of the bracket, whereas the rear end of the shaft 60 receives a bearing in a sleeve 9 clamped in its adjusted position by a split bearing in the rear arm 7^a of the bracket. The escapement wheel is secured to its shaft 6 by screws 10 and 11 that engage at their threaded ends in 65 a flange 12 fixed on the shaft 6. The feed rack 1 engages a feed pinion 13 which is fixed on the forward end of the sleeve 14 which receives its support on the shaft 6. This sleeve is mounted to turn freely on the shaft 70 and carries at its rear end an integral cup-shaped member 15. The circular flange portion of this member 15 has slots cut therethrough to provide internal ratchet teeth 16 as well as external teeth. A pawl 17 is pivoted at 18 on the flange 12 and coacts with the teeth 16 to cause the escapement wheel to turn with the sleeve 14 and the feed pinion 13 when the escapement wheel is released by the feed dogs for letter space movement. This 75 enables the carriage to move from right to left or in the letter feed direction, as indicated by the arrow in Fig. 2. However, when the carriage is returned, or is moved from left to right, the feed pinion 13 and 80 sleeve 14 will turn independently of the escapement wheel, since the pawl 17 acts in but one direction to connect said escapement wheel to turn with the feed pinion. The foregoing features of the typewriting machine are of the usual construction but are 85 explained in detail in order that a better understanding of the counting mechanism actuated from the escapement wheel may be arrived at.

The counting mechanism, and the means by which motion is transmitted to it from the escapement wheel, are mounted as an entirety on a sheet metal bracket comprising a base plate 19 and an upstanding plate 20 100 projecting therefrom. The usual construction of the typewriting machine includes a spring drum supporting bracket 21 secured by screws 22 to the top plate of the machine. I prefer in attaching the counter to the machine to replace the screws 105 ordinarily em-

ployed to secure the bracket 21 in place by the special screws 22 shown. These special screws are tapped to receive screws 23 by which the bracket 19—20 is detachably secured in place on the top plate 2 of the machine. It will be observed that this bracket 19—20 extends transversely of the machine to one side of the escapement wheel and its shaft. An ordinary Veedor stroke counter 24 is secured in place on the base 19 of the bracket by one of the screws 23 and by a screw 25.

The counter is actuated by the usual oscillating crank arm 26 connected to the rock shaft 27 of the counter, and is limited in its oscillating movements in opposite directions by suitable stops comprising stop arms 28 fastened to the shaft 27 and coacting with fixed stops 29 below the stop arms 28, and 20 with corresponding stops (not shown) above the stop arms. In a counter of this character a full stroke of the crank arm 26 in one direction sets up one unit on one of the register wheels 30, whereas a return movement 25 of the crank arm is ineffective on the register.

Motion is transmitted to the crank arm 26 from the escapement wheel by the following means:—

- 30 A screw corresponding to the usual screw 10 is replaced by a longer headed screw 11, which in addition to connecting the escapement wheel to its shaft constitutes a pin offset from the axis of the escapement 35 wheel so as to act as a cam, wiper or actuating device, as will presently appear. A slide or reciprocatory actuating member 31 has a laterally extending headed pin 32, the stem of which is received in a 40 horizontally disposed guide slot 33 in the right-hand edge of the bracket plate 20. One side of the slide 31 rests against the bracket plate 20, whereas the head of the pin 32 bears against the opposite face of said plate 20, 45 thus supporting and guiding the slide on the bracket against movement fore and aft of the machine. It will be seen that the width of the slot 33 is slightly greater than the diameter of the stem of the pin 32 so as to afford 50 a slight up and down movement of the slide at this point, for purposes which will hereinafter appear. The slide 31 is formed with a horizontally disposed slot 34 therein, open at one end. This slot receives the bearing 55 sleeve 9 of the escapement wheel shaft 6. The slide is thus supported near one end by the sleeve 9 for longitudinal reciprocating motion and also to receive a very slight up and down pivotal motion around said sleeve 60 as a center. Two flanges or contacts 35 and 36 project forwardly from the slide 31 on opposite sides of the pin 11 and on opposite sides of the axis of the escapement wheel. The left-hand end of the slide 65 31 is formed with a hook-like pawl 37

adapted to engage the teeth of a ratchet wheel 38. This wheel turns on a pivot 39 by which the wheel is mounted on the front face of the bracket plate 20. A link 40 is pivoted at one end, as at 41, to the ratchet wheel and at its other end, as at 42, to the arm 26 of the counter. A light spring 43 is secured at one end to the base plate 19 of the bracket by a screw 44, whereas the free end portion of the spring is bent rearwardly at right angles to 75 its length, as indicated at 45. This bent end portion of the spring extends beneath and bears with a light pressure upwardly on the left-hand end portion of the slide 31 and projects through an upright slot 46 in the bracket plate 20 to the rear side thereof. The extreme end 47 of the spring is again bent at right angles to the portion 45 thereof to prevent the spring from moving forwardly out of the slot 46. The upwardly directed force of the 80 spring maintains the pawl 37 in engagement with the teeth of the ratchet wheel 38.

In order to prevent an accidental backward movement of the ratchet wheel I have provided a pawl 48 pivoted at 49 on the bracket 90 plate 20, the engaging nose of said pawl being held by gravity in engagement with the teeth of the ratchet wheel.

In the operation of the machine, a return movement of the carriage will turn the feed 95 pinion 13 in a clockwise direction as the parts are viewed from the front of the machine. This motion turns the sleeve 14 and the member 15 without transmitting motion to the escapement wheel or the parts controlled 100 thereby. During a free travel of the carriage in the direction of its feed, as when tabulating or moving the carriage by hand, the feed rack 1 is released from the feed pinion so that no motion is transmitted to the escapement 105 wheel. It is only when the feed dogs are actuated by a printing key or by the space key that motion is transmitted to the escapement wheel and to the counter controlled thereby. At this time the escapement wheel travels in 110 the direction of the arrow in Fig. 1 and in revolving carries the pin 11 against one or the other of the contacts 35 or 36 and operating with camming action thereon moves the slide longitudinally in first one direction and 115 then the other, reciprocating the slide forward and back transversely of the machine. The movement of the slide in one direction steps the ratchet wheel the distance of one tooth and it requires a complete revolution 120 of the escapement wheel to bring about this single tooth movement of the ratchet wheel. During the movement of the slide in the opposite direction the pawl 37 slides over the teeth of the ratchet wheel a distance slightly 125 more than one tooth and engages the next advancing tooth on the ratchet wheel. The motion thus intermittently transmitted from the escapement wheel to the ratchet wheel is in turn transmitted through the link 40 to the 130

arm 26 of the counter. A complete movement of the arm in one direction sets up one unit on the counter, whereas the return movement of the arm during the second half of the revolution of the ratchet wheel 38 has no effect on the counter but merely restores the arm 26 in position to begin another effective stroke.

In the present instance there are fifteen teeth on the escapement wheel, representing fifteen strokes of the keys for each revolution of the wheel. Sixteen ratchet teeth are provided in the present instance on the ratchet wheel. It therefore requires sixteen revolutions of the escapement wheel, or two hundred and forty strokes of the keys, to make a complete revolution of the ratchet wheel and to set up one unit on the counter. Each unit on the register therefore represents two hundred and forty key strokes. According to one system of payment for piece-work, two hundred and forty strokes on the keys is the unit by which the operator is paid. Hence the parts are, in the present instance, constructed and arranged to indicate in accordance with such system. Obviously, however, the intermediate connections between the escapement wheel and the counter may be varied at will to cause a registration on the counter once for a greater or less number of key strokes. A simple method of making such a change is to substitute for the ratchet wheel 38 one having a different number of teeth.

It will be understood that the power of the usual spring drum moves the carriage and transmits motion to the escapement wheel and to the counter controlled thereby, so that none of the resistance due to actuating the counter is exerted against the operator in actuating the keys. It will be seen, moreover, that the resistance to be overcome in actuating the slide 31 and the parts controlled thereby to operate the counter is but slight, adding but little resistance to the spring drum which may be easily and effectively employed to actuate the counter. Such slight drag as may be exerted against the drum is but momentary in the present construction, and is only exerted during the action of the pin 11 on one or the other of the contacts 35 and 36. The pin at other times travels free of both contacts and the slide and the parts controlled thereby, such parts offering no resistance whatever at such times to the free traveling movement of the escapement wheel, or to the travel of the carriage.

In the modern forms of the Nos. 10 and 11 Remington machines, as well as to the No. 12 machine, not only does the yoke-like bracket arms 7^a extend in the rear of the escapement wheel and shaft, but the tabulator frame 50 containing five or more upright tabulator levers 51 are also arranged directly in the rear of the escapement wheel and its shaft. It will be seen therefore that

there is no room at such point to make connection with means for transmitting motion from the escapement wheel shaft to the counter as in the construction disclosed in the Yaw patent hereinbefore referred to. However, by my invention the counter and its actuating mechanism may be readily connected as a single unit, and in the nature of an attachment, to any of such machines without modifying the structural features thereof as they now exist, except by the substitution of screws 11 and 22 of the character shown herein for other screws commonly employed at the corresponding points.

The present construction has all of the additional advantages of the Yaw construction in that the register cannot be fraudulently run up by the operator, as many other counters of the prior art can be. Thus, it will be seen that by the present invention the counter can only be actuated by the finger strokes on the keys and that it would require as much work to run up the register without writing as would be required to produce a corresponding amount of work or written matter.

While I have referred with considerable detail to the use of my invention in the more modern styles of Remington typewriting machines, and while the devices of my invention have been devised more especially for embodiment in such machines, it should be understood that the invention is not restricted to use in such machines, but may be employed in various styles of typewriting machines.

What I claim as new and desire to secure by Letters Patent is:—

1. The combination with a carriage, and an escapement wheel of a typewriting machine that is turned only during the movement of the carriage in a letter-feed direction, of a reciprocatory pawl actuated thereby once for a given plurality of letter space movements of the carriage under control of said wheel, a counter, and transmitting means controlled by said pawl for setting up a unit on said counter for a plurality of reciprocating movements of said pawl.

2. The combination with a carriage, and an escapement wheel of a typewriting machine that is turned only during the movement of the carriage in a letter-feed direction, of a reciprocatory pawl actuated thereby once for a given plurality of letter space movements of the carriage under control of said wheel, a ratchet wheel intermittently actuated by said pawl, a counter, and means controlled by said ratchet wheel for actuating said counter once for a plurality of intermittent actuations of the ratchet wheel.

3. The combination with the escapement wheel of a typewriting machine, of a reciprocatory actuating member controlled thereby and given a complete forward and back

movement for each revolution of the escapement wheel, a pawl carried by said reciprocatory member, a ratchet wheel intermittently actuated by said pawl, a counter having an oscillatory crank arm, and a link connecting said crank arm and ratchet wheel.

4. In a typewriting machine having an escapement wheel, an actuating pin offset from the axis thereof, a reciprocatory actuating slide having contacts on opposite sides of the axis of the escapement wheel and with which said pin coacts to intermittently reciprocate the slide, a counter, and means controlled by said slide for actuating said counter.

5. The combination with the escapement wheel of a typewriting machine having an actuating pin offset from the axis thereof, of a reciprocatory actuating slide having contacts on opposite sides of the axis of the escapement wheel and with which said pin coacts to intermittently reciprocate the slide, a pawl carried by said slide, a ratchet wheel actuated by said pawl, a counter, and means controlled by said ratchet wheel for actuating said counter.

6. The combination of the escapement wheel for a power driven carriage; a shaft for said wheel; a bracket extending in the rear of said shaft for supporting the rear end thereof; a counter; and intermediate operative connections between said escapement wheel and counter for actuating the latter by said wheel, said connections including a reciprocatory slide actuated by said wheel and extending transversely of its axis and forward of that portion of the bracket which supports the rear end of said shaft, a pawl carried by said slide, a ratchet wheel with which said pawl coacts, an oscillatory arm for actuating the counter, and means controlled by said ratchet wheel for intermittently oscillating said arm.

7. The combination of an escapement wheel having an actuating cam connected therewith, a pawl provided with two spaced parallel flanges between which said cam is arranged, a ratchet wheel adapted to be actuated by said pawl, and a link attached at one end to said ratchet wheel and at its other end to an arm connected to a counter.

8. The combination of an escapement wheel having an eccentric pin; a slide having a slot to embrace the axle of said escapement wheel and having also two parallel spaced flanges adapted to be acted upon by said pin whereby said slide is adapted to be moved back and forth once only during one complete revolution of said escapement wheel, a ratchet wheel adapted to be engaged by a tooth on said slide whereby said ratchet wheel is turned only one tooth space distance during one complete revolution of the escapement wheel and one back and forth reciprocation of the slide, a counter, and means for ac-

tuating said counter comprising a link pivotally attached to one end to said ratchet wheel and at its other end to an arm on said counter.

9. In a typewriting machine, escapement mechanism, a camming device operated by said mechanism, and a register and reciprocating driving connections therefor, which, as a unit, are detachably secured to the machine, so that, when in position upon the machine, the driving connections are in the path of the camming device, to be engaged and actuated thereby, upon operation of the escapement mechanism.

10. In a typewriting machine, a main frame; escapement mechanism; a camming device rotating upon operation of said escapement mechanism; and a bracket, a register, and driving means for the register, including a ratchet-wheel, a pawl-carrying arm for driving the ratchet-wheel, and means for imparting motion to said pawl-carrying arm, which, as a unit, are detachably secured upon the rear of said main frame, so that, when in position thereupon, said motion-imparting means occupies a position to be actuated by the camming device and thereby transmits motion to the register to cause the same to operate.

11. In a typewriting machine, a main frame, escapement mechanism, a camming device operated by said mechanism, a bracket detachably secured to the rear of the main frame, a register mounted upon the bracket and reciprocating connections associated with the bracket and actuated by the camming device to impart motion to the register for operating the same.

12. In a typewriting machine, a main frame, escapement mechanism, a camming device rotating upon operation of said escapement mechanism, a bracket secured to the main frame, a register mounted upon the bracket, and means upon said bracket arranged to transpose the rotary motion of said camming device into reciprocating motion and thereby operate the register.

13. In a typewriting machine, a main frame, escapement mechanism, a camming device rotating upon operation of said escapement mechanism, a bracket detachably secured at the rear of said main frame, a register mounted upon the bracket, and means for effecting a step-by-step movement of the register, including a ratchet-wheel, a pawl-carrying arm for driving the ratchet wheel, and means actuated by said camming device for driving said pawl-carrying arm.

14. In a typewriting machine, a carriage-escapement mechanism including a revoluble cam, a bracket detachably mountable on the frame of the machine, a register fixed to the bracket, and driving connections for the register, including an arm rocked by said cam whereby to operate the register.

15. In a typewriting machine; a carriage

escapement mechanism including an escapement wheel; a counter; and driving connections intermediate said escapement wheel and counter including a ratchet wheel, a reciprocating pawl for actuating said ratchet wheel, a pawl coating with said ratchet wheel for preventing a rotation thereof in one direction, means controlled by said es-

capement wheel for reciprocating said pawl, and means for actuating said counter from 10 said ratchet wheel.

Signed at the borough of Manhattan, city of New York, in the county of New York, and State of New York, this 2d day of March, A. D. 1923.

ARTHUR W. SMITH.
